(57) **CLAIM**

The ornamental design for a shoe, as shown and described.

DESCRIPTION

FIG. 1 is a perspective view of a shoe, showing my new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken lines in the drawings depict portions of the shoe that form no part of the claimed design. Portions of the broken lines along the lower portion of the sole as illustrated in FIGS. 2 and 3, have been omitted in the side elevation views (FIGS. 4 and 5) in order to avoid bleeding of the broken and claimed lines.

Contour lines in the drawings represent the contoured surfaces of the claimed design and do not illustrate material, surface ornamentation, or surface decoration.
